UNITED STATES PATENT OFFICE.

HARRY HALL, OF LEICESTER, ENGLAND, ASSIGNOR TO UNITED SHOE MACHINERY COMPANY, OF PATERSON, NEW JERSEY, A CORPORATION OF NEW JERSEY.

HEEL-NAILING MACHINE.

1,119,822.

Specification of Letters Patent.

Patented Dec. 8, 1914.

Application filed July 24, 1909. Serial No. 509,334.

To all whom it may concern:

Be it known that I, HARRY HALL, a subject of the King of England, residing at Leicester, in the county of Leicester, England, have invented certain Improvements in Heel-Nailing Machines, of which the following description, in connection with the accompanying drawings, is a specification, like reference characters on the drawings indicating like parts in the several figures.

This invention relates to heel nailing machines and more particularly to a machine of the type in which a nail block is mounted for movement between a nail receiving position and a nail driving position in which it lies beneath a support upon which the work is positioned.

In machines of this type the work is commonly clamped between a presser member and a plate having nail passages formed therein and the conduits of the nail block are arranged in axial alinement with said passages in the nail driving position of the nail block in order that the nails may be driven through the plate into the work. To insure the accurate guiding of the nails substantially throughout their entire movement into the work the passages in the supporting plate have previously been formed of substantially the same size as the conduits in the nail block. This construction while insuring the accurate guiding of the nails into the work has, however, been open to a number of practical objections. For example, the parts of the machine had to be very carefully formed and adjusted to insure that in the nail driving position of the nail block the conduits of the latter would be in exact actual alinement with the nail passages in the supporting plate. Moreover after the machine had been used for any length of time there was always liability of the parts becoming so worn that the nail drivers within the conduits in the nail block would strike the work supporting plate in their upward movement and thus cause breakage of the parts of the machine.

An object of the present invention is to provide a heel nailing machine of the above class which shall be free from the objections previously mentioned.

With this object in view the present invention contemplates the provision in a heel nailing machine of the above type having

a presser member and a nail block arranged for relative approaching movement to subject the work to clamping pressure, of a yielding member for supporting the work while it is being centered or positioned, arranged between the presser member and nail block in close proximity to the latter. With this arrangement in the relative approaching movement of the presser member and nail block the yielding work support serves merely to transmit the clamping pressure from these parts to the work, the yielding support itself being maintained in operative position by engagement with the rigid nail block. Accordingly the work support may be made so thin that no appreciable distance will exist between the top of the nail block and the work upon the work support.

With this construction the nail conduits in the nail block serve to guide the nails substantially throughout their entire movement into the work so that the nail passages in the work support may be made larger than the said conduits without interfering with the guiding of the nails. By having the passages in the work support larger than the conduits in the nail block less accuracy is required in assembling the parts of the machine than would otherwise be the case and liability of the nail drivers striking the lift support is removed.

Other features of the present invention will be hereinafter described in the specification and pointed out in the claims.

In the drawings,—
Figure 1 is a view in vertical section of a portion of a heel building machine showing one embodiment of the present invention applied thereto; Fig. 2 is a plan view of the parts of the machine shown in Fig. 1, a portion of the heel upon the lift support being removed to show the construction.

One embodiment of the present invention is herein shown applied to a heel building machine having a lift support provided with suitable means for assembling the lifts thereon and a nail block having contained drivers mounted for movement between a nail receiving position and a position beneath the lift support, in which nails may be driven into the lifts assembled upon the support, similar to that shown in the British Patent to William R. Barclay and Arthur Bates No. 24,545/06.

Referring to the drawings, 2 designates the nail block, having contained drivers 4, which is mounted for movement in a horizontal plane between a nail receiving position and a nail driving position beneath the lift support 6. To this end the nail block is carried upon the end of a horizontal arm 8 pivotally mounted upon a vertical stud 10 carried by the frame of the machine, the arrangement being such that the arm can be swung about the stud 10 as a pivot to move the nail block from a nail receiving position to a nail driving position beneath the lift support 6. The machine is also provided with a presser head 12 which is mounted for movement into and out of a position in which it bears upon the lifts assembled upon the lift support in order that it may clamp the heel in operative position prior to the nail driving operation.

The lift support 6 is formed of thin resilient material, such as thin sheet metal, and is provided with nail passages 14, one for each of the drivers 4, the said passages being somewhat larger than the conduits 16 in the nail block. The lift support 6 is yieldingly attached to the head 18 of the machine by means of spring-pressed pins 20. The pins 20 extend respectively into recesses 22 formed in the head of the machine, and the upper ends of springs 24 arranged about the pins press against shoulders formed in the recesses, and the lower ends of the springs press against enlargements formed on the pins so that the heads 26 of the pins press the lift support 6 yieldingly against the head of the machine. With the above construction, should the drivers 4 accidentally come into contact with the lift support it will yield under their pressure by reason of its flexibility and also by reason of its being yieldingly held down in engagement with the head of the machine thus avoiding breakage of the parts of the machine. The upper surface of the nail block being solid, except for the presence of the nail conduits, is adapted to sustain the lift support against the pressure it is subjected to when the work is clamped by the presser head upon said support.

Instead of the lift support 6 being formed with a nail passage for each driver it is obvious that it can be formed in other ways. For example, an aperture in the shape of a heel might be provided sufficiently large to permit the passage of all the drivers. In this case the edges of the support would serve to sustain the heel lifts while they are being assembled and centered by the centering device. If desired, the lift support 6 may be provided with a slit or slits to increase its flexibility.

It will be noted in the construction shown that as the downward pressure exerted by the presser head upon the heel is resisted

by the nail block the work support may be made very thin, it being only necessary that said support should have sufficient strength to support the heel lifts while they are being assembled thereon. By forming the work support of thin material the nail passages therein may be made larger than the nail conduits in the nail block without interfering with the guiding of the nails into the work as said conduits serve to guide the nails throughout substantially their entire movement into the work. By having the passages in the work support larger than the conduits in the nail block, liability of said passages becoming out of alignment with said conduits is avoided.

Having described my invention, what I claim as new and desire to secure by Letters Patent of the United States is:—

1. In a heel nailing machine, the combination with a nail block, mounted for movement between a nail receiving and a nail delivering position, and a presser member arranged for relative approaching movement, of a work support of thin material yielding in the direction of movement of the presser member and sustained between said parts in close proximity to said nail block.

2. A heel nailing machine, having in combination, a heel support, means for driving nails into the lifts assembled thereon including a nail block having drivers arranged therein and arranged to pass through said support, and means independent of the nail block for sustaining said support constructed to allow it to yield away from the nail block.

3. In a heel nailing machine, the combination of a nail block movable into and out of nail driving position and having nail guiding conduits, and a normally stationary yieldable lift support of thin sheet material having holes which register with the conduits in the nail block when the latter is in nail driving position, the said holes being larger than the said conduits, whereby slight inaccuracies in positioning the nail block will not prevent driving nails from the nail block into the heel.

4. A heel nailing machine, having in combination, a nail block mounted for movement between a nail receiving and a nail driving position and a work support comprising a thin flexible member arranged to support the work in close proximity to the upper surface of the nail block when the latter is in its nail driving position.

5. In a heel nailing machine, the combination of a nail block having nail guiding conduits and a yieldable lift support of thin sheet material having holes arranged to register with the said conduits when the parts are in nail driving position, the nail block and the lift support being relatively movable into and out of operative relation, and

the holes in the lift support being substantially larger than the conduits in the nail block, whereby inaccurate register of the parts will not prevent proper driving of 5 the nails into the heel.

6. A heel nailing machine, having in combination, a nail block mounted for movement between a nail receiving position and a nail driving position opposite the work, 10 substantially stationary means for sustaining the work and a presser member for pressing the work toward the nail block, the said work sustaining means being thin and flexible to allow the pressure imparted to 15 the work by the presser member to be resisted by the nail block.

7. In a machine of the class described, the combination of a nail block provided with nail conduits and a work support having 20 nail passages larger in area than the con-

duits in the nail block, the work support being so thin as to have no effect upon the nail driving operation and the nail block and work support being capable of relative lateral movement.

8. In a heel nailing machine, the combination of a nail block movable horizontally from nail receiving to nail driving position and a horizontally stationary, vertically yielding work supporting member arranged 30 to rest upon the nail block when the latter is in nail driving position.

In testimony whereof I have signed my name to this specification in the presence of two subscribing witnesses.

HARRY HALL.
